(57) **CLAIM**

The ornamental design for a mobile phone case substantially as shown and described.

DESCRIPTION

FIG. 1 is a perspective view of a mobile phone case showing a first embodiment of our new design;

FIG. 2 is a front view of the mobile phone case of the FIG. 1;

FIG. 3 is a back view of the mobile phone case of the FIG. 1;

FIG. 4 is a left view of the mobile phone case of the FIG. 1; FIG. 5 is a right view of the mobile phone case of the FIG. 1;

FIG. 6 is a top view of the mobile phone case of the FIG. 1; FIG. 7 is a bottom view of the mobile phone case of the FIG. 1;

FIG. 8 is an enlarged view of the encircled area 8 of FIG. 3; FIG. 9 is an enlarged view of the encircled area 9 of FIG. 3; FIG. 10 is an enlarged view of the encircled area 10 of FIG. 3;

FIG. 11 is an enlarged view of the encircled area 11 of FIG. 4;

FIG. 12 is an enlarged view of the encircled area 12 of FIG. 6;

FIG. 13 is an enlarged view of the encircled area 13 of FIG. 7;

FIG. 14 is a perspective view of a mobile phone case showing a second embodiment of our new design;

FIG. 15 is a front view of the mobile phone case of the FIG. 14;

FIG. 16 is a back view of the mobile phone case of the FIG. 14;

FIG. 17 is a left view of the mobile phone case of the FIG. 14;

FIG. 18 is a right view of the mobile phone case of the FIG. 14;

FIG. 19 is a top view of the mobile phone case of the FIG. 14;

FIG. 20 is a bottom view of the mobile phone case of the FIG. 14;

FIG. 21 is an enlarged view of the encircled area 21 of FIG. 16;

FIG. 22 is an enlarged view of the encircled area 22 of FIG. 16;

FIG. 23 is an enlarged view of the encircled area 22 of FIG. 17;

FIG. 24 is an enlarged view of the encircled area 24 of FIG. 19;

(Continued)

FIG. 25 is an enlarged view of the encircled area 25 of FIG. 20;
 FIG. 26 is a perspective view of a mobile phone case showing a third embodiment of our new design;
 FIG. 27 is a front view of the mobile phone case of the FIG. 26;
 FIG. 28 is a back view of the mobile phone case of the FIG. 26;
 FIG. 29 is a left view of the mobile phone case of the FIG. 26;
 FIG. 30 is a right view of the mobile phone case of the FIG. 26;
 FIG. 31 is a top view of the mobile phone case of the FIG. 26;
 FIG. 32 is a bottom view of the mobile phone case of the FIG. 26;
 FIG. 33 is an enlarged view of the encircled area 33 of FIG. 28;
 FIG. 34 is an enlarged view of the encircled area 34 of FIG. 28;
 FIG. 35 is an enlarged view of the encircled area 35 of FIG. 28;
 FIG. 36 is an enlarged view of the encircled area 36 of FIG. 29;
 FIG. 37 is an enlarged view of the encircled area 37 of FIG. 31; and,
 FIG. 38 is an enlarged view of the encircled area 38 of FIG. 32.
 The dot-dash broken lines in the drawing figures delineate portions of the mobile phone case, including claimed subject matter, that are shown on an enlarged scale in FIGS. 8-13, 21-25, and 33-38. The dashed broken lines throughout the drawing figures depict portions of the mobile phone case that form no part of the claimed design. The dot-dash and dashed broken lines form no part of the claimed design.

1 Claim, 38 Drawing Sheets
